INVENTORS.

United States Patent Office.

JESSE B. JOHNSON AND THOMAS E. JOHNSON, OF INDIANAPOLIS, INDIANA.

Letters Patent No. 97,777, dated December 14, 1869.

LUMBER-DRIER.

The Schedule referred to in these Letters Patent and making part of the same

We, JESSE B. JOHNSON and THOMAS E. JOHNSON, of Indianapolis, in the county of Marion, and State of Indiana, have invented certain Improvements in Driers, of which the following is a specification.

Nature and Objects of the Invention.

Our invention relates to the combination of the furnace used in the drier, patented by Jesse B. Johnson, March 10, 1868, numbered 75,277, and a drying-chamber, furnished with deflectors, and trucks for holding the lumber, and ventiducts, arranged in such a manner as to more uniformly distribute the heated air throughout the drying-chamber, especially near the floor, and thus to avoid the necessity of handling the lumber, or changing its position, in order to dry it uniformly at bottom and top.

Description of the Accompanying Drawings.

Figure 1 is a vertical longitudinal section of a drying-kiln embodying our invention.

Figure 2 is a transverse section of the same.

General Description.

A are the walls of the drying-chamber, which may be built of any suitable material, and in any suitable manner.

The furnace B, the top of which is covered with cobble-stones or other analogous material, substantially in the manner described in the Letters Patent, No. 75,277, issued to Jesse B. Johnson, March 10, 1868, is situated at one end, and across the drying-chamber, as shown.

This furnace may be connected with a chimney or flue, as mentioned in the Letters Patent already referred to, for the purpose therein described.

A curved deflecting-plate, C, is arranged over the furnace B, hung on a rod extending through the side of the drying-chamber, and furnished with a lever on the outside, by which the deflecting-plate may be raised and lowered at pleasure, and thus be made to subserve a double purpose, viz:

First, to cover the top of the furnace in starting the fire, causing all the products of combustion to pass off through the flue; and

Second, to be turned up at such an angle, as shown in fig. 1, as to give a horizontal direction to the heated

air and products of combustion as they rise through the boulders into the lower part of the lumber.

D are vertical deflecting-plates, made of metal or other suitable material, hung to the sides of the building, and held by springs, or otherwise, in such manner as to rest against the lumber on the sides, for the purpose of directing the currents of heated air into and among it; and

E are horizontal plates, of a similar kind, and for a similar purpose, hung to the ceiling of the drying-chamber.

The trucks or ears upon which the lumber is piled, for convenience of running it into and out of the drying-chamber, are made with longitudinal strips H, resting on the top of the truck-frames upon which the lumber is piled.

The spaces between the pieces H form flues for the passage of the heated air and products of combustion beneath the lumber, and then, together with the side and top deflecting-plates D and E, and the openings into the flue G, situated near the floor of the drying-chamber, will, to a great extent, overcome the tendency of the heated air to rise, and thus cause a more equal distribution of it low down in the drying-chamber, and hence will dry the lumber more uniformly throughout the kiln.

G are ventiducts, built in any approved manner, and situated at the end of the drying-chamber, opposite the furnace, for the escape of the air after it has circulated among the lumber. The openings into these flues are situated near the floor of the drying-chamber.

Claim.

We claim, as our invention—

Furnishing the drying-chamber with the vertical deflecting-plates D, and the horizontal deflecting-plates E, arranged substantially as set forth, in combination with the furnace B, curved deflecting-plate C, ventiducts G, and longitudinal ducts formed by the pieces H resting on the top of the truck-frame, all arranged and operating substantially as and for the purpose set forth.

JESSE B. JOHNSON.
